UNITED STATES PATENT OFFICE

2,656,811

BOAT ANCHOR

Denver D. McRae, Ivanhoe, Tex.

Application August 21, 1951, Serial No. 242,867

4 Claims. (Cl. 114—208)

1

This invention relates to a boat anchor.

An object of this invention is to provide an anchor which will efficiently operate on different types of lake bottoms, and have good holding ability on every bottom.

Another object of this invention is to provide an anchor of construction and weight that gives good holding power on tough clay, and which will dig into hard-packed sand, as well as having good holding power in soft mucky bottoms.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Fig. 1 is a view in side elevation of an anchor constructed in accordance with this invention.

Fig. 2 is a top plan view.

Fig. 3 is a view in rear elevation.

Fig. 4 is a transverse, sectional view, taken on line 4—4, Fig. 1, and looking in the direction of the arrows.

Fig. 5 is a transverse, sectional view, taken on line 5—5, Fig. 1, and looking in the direction of the arrows.

Referring to the drawings, in which the preferred embodiment of this invention is illustrated, 1 is a frame of substantially U-shape. A shank 2 is provided with two arms 3, which are turned inwardly at their inner ends 4, Fig. 5, and these ends 4 are secured by bolts 5 to the inner face of the end 6 of the frame 1. A weight 7 is within the frame 1, in front of ends 4, and this weight is secured in position by means of a bolt 8 that extends through the rear end of the frame 1. This weight 7 is cut away at 9 on its top and bottom, these cut-away portions 9 registering with the arms 3 of the shank 2. As shown in Figs. 2, 4 and 5 these cut-away portions are wider and deeper on the side of the member 7 than at the opposite side. A ring 10 is mounted on the shank 2 and slides freely on the arms 3. As is clearly shown in the drawings the diameter of the material of which the ring is made is less than the distance between the deeper end of the cut-away 9 and the adjacent portion of the shank arm 3. The cut-away portions thus permit the ring 10 to move into position between the weight 7 and an arm 3, the tapering of the cut-away effecting jamming or gripping of the ring in such position. When the anchor is in use, the usual chain or cable (not shown) is attached to ring 10, and when the anchor is holding the boat in a rela-

2

tively stationary position, the strain will be on the outer end of shank 2. When the operator wishes to move the boat, he operates the ring 10 until it moves backward on one of the arms 3 until the ring is positioned in one of the cut-away portions 9, whereupon the anchor can be lifted to remove it from its anchoring position. In other words, the lifting position is when the ring 10 is at the rear of the anchor, with the ring having a portion between one of the arms 3 and the weight 7.

Bolts 11 extend outwardly from the sides of the frame 1, with their inner ends extending through the sides. On the inner end of the bolts are nuts 12. A washer 13 is on each bolt against the fluke 14 and a nut 15 is on the bolt against the washer 13, Fig. 2. A bushing 16 is on each bolt, Fig. 5, on which is loosely mounted the fluke 14. The washer 13 is against the outer end of the bushing 16. The fluke 14 has a relatively free swinging movement on the bushing.

Each fluke 14 comprises an elongated plate having inner and outer flanges 17 and a second flange extending longitudinally thereof at the center section of said fluke plate as a reinforcing rib. Each fluke plate 17 is cut away at 18. The frame 1 is also cut away at 19. When the fluke 14 is in its down position, Fig. 1, the cut-away portion 18 will be engaging the cut-away portion 19. When the fluke 14 is in its raised position, the cut-away portions 18 will bear against the front edge of the side of frame 1.

The bolts 11 not only provide the means for mounting the flukes on the frame 1, but they also hold the anchor in an operative position, including the preventing of the anchor from turning over, which would retard the function of the anchor by reason of preventing the flukes from digging into the ground.

While I have described the preferred embodiment of the invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an anchor of the class described, a frame of plate metal having a central portion and a pair of frame arms extending at right angles from said central position, a shank formed from a strip of flat metal bent at its center to provide an arcuate portion and having shank arms di-

verging from the arcuate portion and provided with inturned ends resting on the central portion of the frame, securing bolts extending the inturned ends and frame and holding the shank rigidly on the frame, a ring for cable attachment slidably engaged on said shank, stock arms projecting in alignment outwardly from the frame arms, and fluke members swingingly mounted on said stock arms.

2. In an anchor of the class described, a frame of plate metal having a central portion and a pair of frame arms extending at right angles from said central position, a shank formed from a strip of flat metal bent at its center to provide an arcuate portion and having shank arms diverging from the arcuate portion and provided with inturned ends resting on the central portion of the frame, securing bolts extending the inturned ends and frame and holding the shank rigidly on the frame, a ring for cable attachment slidably engaged on said shank, stock arms projecting in alignment outwardly from the frame arms, and fluke members each consisting of an elongated plate having inner and outer flanges and a second flange extending longitudinally thereof at the center section of the fluke plate as a reinforcing rib, said stock arms each projecting through a respective fluke plate adjacent one end, each fluke plate resting against the outer face of a respective frame arm, the said inner flanges extending across the edges of the frame arms to engage said frame arms and limit swinging movement of the fluke members.

3. In an anchor of the class described, a frame of plate metal having a central portion and a pair of frame arms extending at right angles from said central position, a shank formed from a strip of flat metal bent at its center to provide an arcuate portion and having shank arms diverging from the arcuate portion and provided with inturned ends resting on the central portion of the frame, securing bolts extending the inturned ends and frame and holding the shank rigidly on the frame, a ring for cable attachment slidably engaged on said shank, stock arms projecting in alignment outwardly from the frame arms, fluke members swingingly mounted on said stock arms, a weight engaged between the shank arms adjacent their inturned ends, said weight being of generally cylindrical form and having cut-away portions adjacent the shank arms increasing in width and depth away from the portion of the weight nearest the frame center to provide ring

space, and a securing bolt extending through the center of the frame and through said weight.

4. In an anchor of the class described, a frame of plate metal having a central portion and a pair of frame arms extending at right angles from said central position, a shank formed from a strip of flat metal bent at its center to provide an arcuate portion and having shank arms diverging from the arcuate portion and provided with inturned ends resting on the central portion of the frame, securing bolts extending the inturned ends and frame and holding the shank rigidly on the frame, a ring for cable attachment slidably engaged on said shank, stock arms projecting in alignment outwardly from the frame arms, fluke members each consisting of an elongated plate having inner and outer flanges and a second flange extending longitudinally thereof at the center section of the fluke plate as a reinforcing rib, said stock arms each projecting through a respective fluke plate adjacent one end, each fluke plate resting against the outer face of a respective frame arm, the said inner flanges extending across the edges of the frame arms to engage said frame arms and limit swinging movement of the fluke members, a weight engaged between the shank arms adjacent their inturned ends, said weight being of generally cylindrical form and having cut-away portions adjacent the shank arms increasing in width and depth away from the portion of the weight nearest the frame center to provide ring space, and a securing bolt extending through the center of the frame and through said weight.

DENVER D. MCRAE.
